DEVICE FOR CLEANING WINDOWS

Howard A. Eklind, Chicago, Ill.

Application July 2, 1956, Serial No. 595,263

10 Claims. (Cl. 15—121)

The present invention relates in general to cleaning devices, and has more particular reference to a window washing instrument of a sort especially well adapted for washing and drying the outer surfaces of double-hung sash windows from the interior of the structure containing the same.

In cleaning double-hung sash windows, it is extremely difficult, if not impossible, by conventional procedures, to wash the outer surfaces of the windows except by starting or sitting on the window sill outwardly of the window. Heretofore, as disclosed, for example, in U.S. Letters Patents Nos. 2,537,482, 2,572,112 and 2,649,600, which issued respectively to Charles Reilly, on January 9, 1951; to Jerome T. Coppe, on October 23, 1951, and to Pratt R. Loveland, on August 25, 1953, devices have been proposed for aiding in the cleaning of double-hung sash windows, but such devices have been cumbersome and relatively hard to manipulate.

An important object of the present invention is to provide a simple, handy device for cleaning all window surfaces while standing, or otherwise disposed, at the inner side of the window structure; a further object being to provide a device of the character mentioned adapted for manipulation entirely from the inner side of the window structure being cleaned, to wash and dry all of the window surfaces of the structure.

Another important object is to provide an instrument formed with a washing sponge at one end and a wiping squeegee device at the other; said instrument being of exceedingly thin configuration, whereby the sponge and squeegee may alternately be inserted between double-hung window sashes to permit application thereof to sash window surfaces for the washing and drying of the same; a further object being to mount the sponge and squeegee components at the opposite ends of a support frame, comprising resilient metal wires, so that the frame may be readily applied and manipulated between the components of a double-ring sash window structure.

Another important object is to provide a relatively thin frame structure carrying a flat window washing sponge component at one end and a window drying squeegee component at the other, wherein the frame is separable medially of said sponge and squeegee components to provide a squeegee carrying frame portion and a sponge carrying frame portion, said portions being provided with cooperating latch means to hold the same firmly, yet detachably in end to end abutting relationship; a further object being to provide an improved latch structure lying entirely within the confines of the thin frame structure, whereby the latch means may slide freely between the sash components of a double-hung window structure.

Briefly stated, the invention, in accordance with a preferred aspect, contemplates the provision of a window cleaning implement comprising separable frame portions adapted to be detachably latched in end to end abutting relationship to form a relatively thin, elongated frame structure embodying spaced apart wire-like rods of rel-

2

atively stiff, springy material, the frame, including the means for latching the portions thereof together, being sized for facile insertion between the sash of a double-hung window structure, and having a preferably rectangular window washing sponge mounted at one end of said frame, the frame, at its sponge remote end, carrying a window wiping squeegee, said sponge and squeegee being secured upon preferably metal mounting plates integrally united and secured, as by welding, to the frame forming rods, at the opposite ends of the frame, to thereby secure said rods in spaced apart frame forming position.

The foregoing and numerous other important objects, and advantages and inherent functions of the invention will become apparent as the same is more fully understood from the following description, which, taken in connection with the accompanying drawings, discloses a preferred embodiment of the invention.

Referring to the drawings:

20 Fig. 1 is a perspective view of a window washing device embodying the present invention;

Fig. 2 is an exploded view showing, in perspective, the components of a portion of the window washing device;

25 Figs. 3 and 4 are sectional views taken substantially along the lines 3—3 and 4—4 in Fig. 1;

Fig. 5 is a plan view showing a modified construction of a portion of the device shown in Fig. 1;

25 Figs. 6 and 7 are sectional views taken substantially along the lines 6—6 and 7—7 in Fig. 5; and

30 Fig. 8 is a perspective view of a portion of the device.

To illustrate the invention, the drawings show a window cleaning instrument 11 comprising an elongated frame 12 carrying a sponge 13 and a window drying squeegee 14 at opposite ends of the frame.

The frame 12 is of unusually thin character, and hence adapted for insertion between the relatively slideable sashes of a double-hung window structure, when the sashes are in relatively overlapping position, as when 40 one or both are in partly or fully open position. To this end, the frame 12 preferably comprises metal rods or bars 15 disposed in spaced apart, preferably parallel relationship. The rods or bars 15 may conveniently comprise resilient steel wire stock having diameter of the order of three-sixteenths of an inch. The frame 12 also 45 may comprise a plurality of separable sections detachably secured together in end to end relationship, the device shown embodying a pair of separable frame sections 16 and 16' formed with readily operable latch means 17 for detachably securing the sections 16 and 16' in abutting end to end relationship, to thereby support the sponge 13 and squeegee 14 at the opposite ends of the frame.

The sponge and squeegee are also of relatively thin 55 configuration, adapted for insertion between the sashes of a double-hung window structure when in partially overlapped relationship, whereby the sponge and the squeegee may be successively applied between overlapped sashes for the purpose of washing and drying the outwardly facing window surfaces of the inner sash. By 60 providing a separable frame 12, the sponge and squeegee may be manipulated and employed as separate elements, if desired.

Where relatively small windows are to be washed, the 65 sponge carrying frame portion may first be inserted between the sashes, after which the squeegee carrying frame portion may be attached to the sponge remote end of the sponge carrying frame portion, in order to provide an extended handle for manipulating the sponge in position 70 between the overlapped sashes. Conversely, the squeegee carrying frame portion may be applied between a pair of sash window components, after which the sponge carrying

frame component may be attached to the squeegee remote end of the squeegee carrying frame component, in order to serve as a manipulating handle therefor.

As shown, both the sponge and squeegee carrying frame components or sections 16 and 16' may comprise a length of wire stock bent medially, as at 18, to form the parallel, spaced apart rod portions 15. The sponge 13 and squeegee 14 may be supported upon preferably metal mounting plates 19 and 19' respectively welded or otherwise firmly secured to the frame sections 16 and 16' at the medial bent portions 18 thereof. It will be obvious, of course, that the frame sections 16 and 16' may each comprise a pair of separate rod elements secured in parallel spaced relation upon the mounting plates 19 and 19', although, as a manufacturing convenience, it is expedient to medially bend a single piece of wire, as at 18, to form the parallel frame portions 15 and to weld the frame component, with its associated mounting plate 19 or 19', at and adjacent its medial bent portion 18.

The washing component 13 preferably comprises a pad of sponge rubber or the like, having rectangular configuration, whereby the corners of the pad may extend in corresponding corners of a window to be washed. The sponge may be cemented or otherwise securely fastened upon the mounting plate 19, which has a generally rectangular mounting portion 20 which preferably is of somewhat smaller area than the sponge 13. The marginal edges of the sponge, as a consequence, may extend beyond the marginal edges of the plate portion 20. The sponge mounting plate 19 may also include a frame engaging extension 21 projecting laterally of the sponge mounting portion 20, the frame section 16 being weldingly secured to the plate portion 21.

The window wiping member 14 preferably comprises a squeegee which may consist of a strip of resilient rubbery material 22 having a flexible wiping edge 23, along one side thereof, a medial shoulder 24 extending longitudinally of the strip and facing toward the wiping edge, and a mounting edge 25 of rounded configuration along the side of the strip remote from the wiping edge 23. In order to stiffen the squeegee strip 22 along its mounting edge 25, the same may be held in a bent sheet metal channel 26 having a web 27 underlying the bottom side of the strip adjacent the edge 25, and an integrally connected web 28 overlying and enclosing the strip between the edge 25 and the shoulder 24, the marginal edge of the web 28 being formed with an inturned lip 29 for locking engagement with the shoulder 24.

The squeegee mounting plate 19' has a portion 30 to which the section 16' is weldingly secured, an offset flange 31 weldingly or otherwise secured to the medial portions of the squeegee support channel 26, and an intermediate strengthening groove 32 formed transversely of the mounting plate 19' between the mounting portion 30 and the squeegee supporting flange 31.

While the frame forming bars 15 may extend uninterruptedly between the sponge and squeegee mounting plates 19 and 19', the same, in the illustrated embodiment, are intersected, medially of the mounting plates, to form the separate frame sections 16 and 16', the latch means 17 serving to detachably interconnect the frame sections with the rod portions 15 thereof in abutting end to end relationship.

The latching means 17, as shown more particularly in Figs. 4-7 of the drawings, preferably comprises a pair of cooperating sheet metal strips 33 and 34 respectively extending between and having the opposite end portions thereof wrapped around and solderingly or weldingly secured to the plate remote ends of the bars 15 of the frame sections 16 and 16', the strip 23 being thus secured on one frame section, while the strip 34 is secured upon the other. One of the strips may be formed with a depressible latching member adapted to latchingly engage a detent formed in the other strip when the frame sections 16 and 16' are brought into alined latching abutment.

To aid in so bringing the frame sections into latching alinement, one of the latch forming strips may be mounted on its carrying frame section behind or inwardly of the terminal ends 35 of the frame forming rods 15 thereof, whereby said rod ends may extend outwardly of or beyond the latch forming strip. The other of said latch forming strips may be mounted on its carrying frame section in position extending outwardly of or beyond the ends of the frame forming bars 15 thereof, in order that the opposite curled edges of the strip may form tubular pockets outwardly of and in alinement with the frame forming bars 15 of said section, said pockets being disposed in position to slidingly receive the projecting ends 35 of the frame forming bars of the other frame section.

As shown more particularly in Figs. 4-7, the strip 33 is mounted on the rods 15 of the frame section 16 in position inwardly of the terminal ends 35 of said rods, whereby to form said terminal ends as guide prongs extending outwardly of or beyond the strip 33, the opposite end edges 33' of the strip 33 being curlingly wrapped about and solderingly or weldingly secured to the frame forming rods 15 of the frame section 16. The strip 34, however, has its opposite edge portions 34' curved to generally cylindrical pocket forming configuration, the ends of the frame forming rods 15 of the frame section 16' being received and solderingly or weldingly secured in the end portions only of the pockets formed by said cylindrically curled edge portions 34'. The remaining portions of said pockets are adapted to guidingly receive the prongs 35 formed by the projecting ends of the rods 15 of the other frame section, when the said frame sections are brought together in end to end abutting relationship. The curled edge portions 34' of the strip 34 thus serve to interconnect and support the frame sections in end abutting relationship.

In order to latchingly secure the frame sections together in end abutting relationship, the latching means 17, as shown more particularly in Fig. 4, may comprise a latching detent 36 formed on one of the frame sections in position to latchingly engage with a latch shiftably supported on the other frame section, said detent 36 preferably comprising an offset edge formed at one side of an opening 38 formed in the strip 34 preferably medially of the curved end edge portions thereof.

The latch 37, as shown in Fig. 4, may comprise an outwardly struck portion formed in a tongue 39, which may comprise an integral extension of the strip 33 which projects therefrom medially between the projecting ends 35 of the frame forming rods. The tongue 39 resiliently supports the latch 37 in position to engage the detent 36 when the frame sections are brought together in end abutting latching relationship, the latch carrying end of the tongue 39 extending in the opening 38 when the parts are in relatively latched position. By pressing upon said latch carrying end of the tongue, in said opening, the latch 37 may be released from its engagement with the detent 36, thereby permitting the frame sections to be separated.

As shown more particularly in Figs. 5, 6 and 7, the latch detent may comprise alined and mutually facing notches 36' formed in the projecting ends 35 of the frame forming rods of the frame section 16. The latch may comprise projecting portions 37' of a tongue 39' formed on the strip 34 preferably medially thereof, as by striking the tongue 39' from the medial portions of the strip 34 while leaving the same resiliently connected with the strip, as at the end of the tongue 40 remote from the latching projections 37'. The latching projections 37', accordingly, may be supported in position to latchingly engage in the detent forming notches 36' when the frame sections 16 and 16' are brought together in end abutting relationship; and the projecting ends 35 of the frame forming rods may be formed with cam surfaces 41, in position to guidingly engage the latching projections 37' in order to steer the same into the detent forming notches 36' as

the frame sections are brought into abutting relationship. By pressing upon the tongue 39' adjacent and between the latching projections 37', the same may be released from the notches 36' in order to permit the frame sections 16 and 16' to be separated.

It will be seen from the foregoing that the latching structures 17 are contained within the zone defined by the spaced frame forming rods 15 and do not project outwardly of said zone, but are housed entirely within such zone. The frame latching means of the present invention, accordingly, will not in any way interfere with the insertion of the frame and the movement thereof between the window sashes of a double-hung window structure. The latches, however, are designed to automatically accomplish the latching function in response to arrangement of the frame sections 16 and 16' in end abutting relationship, thereby facilitating the assembly of the frame sections in latched condition. The latches may also be released quickly and easily in response to but slight pressure applied upon the same.

In order to eliminate shoulders where the strips 33 and 34 are attached on the rods 15, the rods may be formed with ends of reduced size to provide seats 45 for receiving the curled edges of the strips 33 and 34, so that the outer surfaces of such curled edges may lie in a common plane with the surfaces of the rods 15 on which mounted and thereby allow the rods 15 and latches to slide freely over and between window sashes.

As shown more particularly in Fig. 8, the rods 15 may be formed with strip receiving seats 45' only on the opposite sides of the rods to provide for the flush mounting of the strips on the rods at the opposite sides thereof only, since it is necessary to eliminate sash engaging shoulders on the frame 12 only at the portions thereof which are likely to engage window sashes when inserted therebetween. As a manufacturing expedient, it is, of course, easier and less expensive to provide seats 45' on the opposite sides only of the ends of the rods 15, as shown in Fig. 8, than it is to provide complete circumferential seats 45 of the sort shown in Figs. 4, 5 and 6.

While the drawings show a window cleaning device comprising a pair of sections adapted to be detachably secured together for use or to be used independently as dictated by convenience, it is within the contemplation of the present invention to provide one or more additional frame sections formed for detachable latching engagement with and between the frame sections 16 and 16' in order that the length of the frame may be correspondingly increased to permit the device to be employed in cleaning outsize window sashes.

It is thought that the invention and its numerous attendant advantages will be fully understood from the foregoing description, and it is obvious that numerous changes may be made in the form, construction and arrangement of the several parts without departing from the spirit and scope of the invention, or sacrificing any of its attendant advantages, the forms herein disclosed being preferred embodiments for the purpose of illustrating the invention.

The invention is hereby claimed as follows.

1. A cleaning device comprising cooperating elongated frame sections of relatively wide and thin sectional character adapted for unhampered movement between the sash components of double-hung windows, and latch means for releasably securing said sections in end-to-end abutting relationship to form an elongated frame, said latch means extending within the width and depth of said sections in position guarded against snagging upon window sash components when the device is in use therebetween, so that a washing sponge and wiping squeegee respectively mounted at the latch remote ends of said cooperating frame sections may be supported respectively at the opposite ends of said elongated frame in position selectively to be applied in window washing position between double-hung window sash components, when said sections are latching interconnected.

2. A cleaning device comprising spaced apart rods of resilient material forming cooperating frame sections of relatively thin sectional character adapted for unhampered movement between the sash components of double-hung windows, and latch means for releasably securing said sections in end-to-end abutting relationship to form an elongated frame, said latch means extending entirely within the zone defined between the spaced rods of said sections in position guarded against snagging upon window sash components when the device is in use therebetween, so that a washing sponge and wiping squeegee respectively mounted at the latch remote ends of said cooperating frame sections may be supported respectively at the opposite ends of said elongated frame in position selectively to be applied in window washing position between double-hung window sash components, when said sections are latching interconnected.

3. A cleaning device comprising spaced apart rods of resilient material forming cooperating frame sections of relatively thin sectional character adapted for unhampered movement between the sash components of double-hung windows, and latch means for releasably securing said sections in end-to-end abutting relationship to form an elongated frame, the spaced rods of one of said frame sections being formed with inwardly facing notches defining latching detents, the other of said frame sections carrying a depressible latch member in position to extend between said notched rods and to engage said latching detents, said latch means extending entirely within the zone defined between the spaced rods of said sections in position guarded against snagging upon window sash components when the device is in use therebetween, so that a washing sponge and wiping squeegee respectively mounted at the latch remote ends of said cooperating frame sections may be supported respectively at the opposite ends of said elongated frame in position selectively to be applied in window washing position between double-hung window sash components, when said sections are latching interconnected.

4. A cleaning device comprising elongated frame sections each embodying a pair of equally spaced rods, and latch means for releasably securing said sections with the rods thereof in end to end abutting relationship, a washing sponge and wiping squeegee respectively mounted at the latch remote ends of said frame sections, said latch means comprising a pair of cooperating sheet metal strips each extending between and secured to the spaced rods of its corresponding section, whereby to support the same in spaced relationship, one of said frame sections being formed with a latching detent and the other carrying a yieldingly depressible latch in position to engage said detent when the sections are in end to end abutting relationship.

5. A cleaning device comprising elongated frame sections each embodying a pair of equally spaced rods, and latch means for releasably securing said sections with the rods thereof in end to end abutting relationship, a washing sponge and wiping squeegee respectively mounted at the latch remote ends of said frame sections, said latch means comprising a pair of cooperating sheet metal strips each extending between and secured to the spaced rods of its corresponding section, whereby to support the same in spaced relationship, one of said frame sections being formed with a latching detent and the sheet metal strip of the other having a portion forming a yieldingly depressible latch in position to engage said detent when the sections are in end to end abutting relationship.

6. A cleaning device comprising elongated frame sections each embodying a pair of equally spaced rods, and latch means for releasably securing said sections with the rods thereof in end to end abutting relationship, a washing sponge and wiping squeegee respectively mounted at the latch remote ends of said frame sections, said latch means comprising a pair of cooperating sheet metal strips each extending between and secured to the spaced rods of its corresponding section, whereby to support the same in spaced relationship, one of said frame sections being formed with a latching detent and the sheet metal strip of the other having a portion forming a yieldingly depressible latch in position to engage said detent when the sections are in end to end abutting relationship.

75

rods of its corresponding section, whereby to support the same in spaced relationship, the strip of one of said frame sections having an edge defining a latch detent and the other frame section carrying a depressible latch in position to engage said detent when the sections are in end to end abutting relationship.

7. A cleaning device comprising elongated frame sections each embodying a pair of equally spaced rods, and latch means for releasably securing said sections with the rods thereof in end to end abutting relationship, a washing sponge and wiping squeegee respectively mounted at the latch remote ends of said frame sections, said latch means comprising a pair of cooperating sheet metal strips each extending between and secured to the spaced rods of its corresponding section, whereby to support the same in spaced relationship, the strip of one of said frame sections having an edge defining a latch detent and the strip of the other section having a tongue forming a depressible latch member in position to engage said detent when the sections are in end to end abutting relationship.

8. A cleaning device comprising elongated frame sections each embodying a pair of equally spaced rods, and latch means for releasably securing said sections with the rods thereof in end to end abutting relationship, a washing sponge and wiping squeegee respectively mounted at the latch remote ends of said frame sections, said latch means comprising a pair of cooperating sheet metal strips each extending between and secured to the spaced rods of its corresponding section, whereby to support the same in spaced relationship, the opposite end edges of said strips being curled about and secured to the rods of the section on which mounted, one of said frame sections being formed with a latching detent and the other carrying a yieldingly depressible latch in position to engage said detent when the sections are in end to end abutting relationship.

9. A cleaning device comprising elongated frame sections each embodying a pair of equally spaced rods, and latch means for releasably securing said sections with the rods thereof in end to end abutting relationship, a washing sponge and wiping squeegee respectively mounted at the latch remote ends of said frame sections, said latch means comprising a pair of cooperating sheet metal strips each extending between and secured to the spaced rods of its corresponding section, whereby to support the

same in spaced relationship, the opposite end edges of one of said strips being curled about and secured to the rods of the section on which mounted to form cylindrical pockets outwardly of said rods to slidably receive the projecting ends of the rods of the other of said sections, one of said frame sections being formed with a latching detent and the other carrying a yieldingly depressible latch in position to engage said detent when the sections are in end to end abutting relationship.

10. A cleaning device comprising elongated frame sections of thin sectional character each embodying a pair of equally spaced rods, and latch means for releasably securing said sections with the rods thereof in end to end abutting relationship, a washing sponge and wiping squeegee respectively mounted at the latch remote ends of said frame sections, said latch means comprising a pair of cooperating sheet metal strips each extending between and secured to the spaced rods of its corresponding section, whereby to support the same in spaced relationship, one of said strips being secured to the rods of a said frame section inwardly of the ends of said rods, to thereby provide projecting rod end portions, the opposite end edges of the other of said strips being curled about and secured to the rods of the section on which mounted in position forming cylindrical pockets extending outwardly of said rods and sized to snugly yet slidably receive said projecting rod end portions, one of said frame sections being formed with a latching detent and the other carrying a yieldingly depressible latch in position to engage said detent when the sections are in end to end abutting relationship.
